UNITED STATES PATENT OFFICE

93,120

DESIGN FOR A GLASS GOBLET OR ARTICLE OF SIMILAR NATURE

Eben H. Mann, Buffalo, N. Y.

Application June 11, 1934, Serial No. 52,133

Term of patent 14 years

To all whom it may concern:

Be it known that I, EBEN H. MANN, a citizen of the United States, residing at Buffalo, in the county of Erie and State of New York, have invented a new, original, and ornamental Design for a Glass Goblet or Article of Similar Nature, of which the following is a specification, reference being had to the accompanying drawing forming a part thereof.

In said drawing:

Figure 1 is an elevation of a glass goblet or article of similar nature embodying my new design.

Figure 2 is a view of the same, half in elevation and half in central vertical section.

I claim:

The ornamental design for a glass goblet or article of similar nature substantially as shown and described.

EBEN H. MANN.
